L. L. DAWSON & J. L. ROACH,
CHEST FOR PISTON VALVES,
APPLICATION FILED SEPT. 27, 1915.

1,184,630.

Patented May 23, 1916.

UNITED STATES PATENT OFFICE.

LANCE L. DAWSON AND JOHN L. ROACH, OF CHILDRESS, TEXAS.

CHEST FOR PISTON-VALVES.

1,184,630.

Specification of Letters Patent. Patented May 23, 1916.

Application filed September 27, 1915. Serial No. 52,930.

To all whom it may concern:

Be it known that we, LANCE L. DAWSON and JOHN L. ROACH, citizens of the United States, residing at Childress, in the county of Childress and State of Texas, have invented new and useful Improvements in Chests for Piston-Valves, of which the following is a specification.

Our present invention pertains to valve chests for steam engines; and it contemplates the provision of a chest fitted for the reception and operation of a piston valve, and constructed with a view to being expeditiously and easily applied to the piston cylinder of a locomotive in the place of a removed slide-valve chest, whereby, without loss of the cylinder, the locomotive may be adapted to use superheated steam and high pressures.

Other advantageous features of the invention will be fully understood from the following description and claim when the same are read in connection with the drawings, accompanying and forming part of this specification, in which:

Figure 1 is a view, partly in end elevation and partly in transverse section, showing our novel chest with the bushing in position and the head removed. Fig. 2 is a view, partly in side elevation and partly in longitudinal-central section, with the heads omitted. Fig. 3 is a fragmentary view showing the internal construction around the peep-hole in the chest and the offset in the web to accommodate said hole. Fig. 4 is a transverse section through the recesses 17^a.

Similar numerals of reference designate corresponding parts in all views of the drawings.

The chest 1 is made of cast-iron, is flat at its underside, is provided throughout its length with a bore 10 for the reception of a bushing 9, Figs. 1 and 2, and is formed at its ends with circular portions 11 in the faces of which are apertures 12, Fig. 1, designed to receive the threaded studs (not shown) through the medium of which the heads (also not shown) are fixed to the ends of the chest. The bushing 9 extends the full length of the chest 1 and is designed to snugly fit in the bore 10 and about at its ends against the before-mentioned heads. Consequently when one of the heads is removed, the bushing and the piston valve (not shown) may be readily removed and as readily replaced with new parts. In prac-

tice steam is present at all times in the end ports, and passes through the end slots of the bushing to the interior thereof. It is then admitted alternately into the ends of the cylinder by the action of the reciprocating valve (not shown) uncovering first one and then the other of the admission ports. At its base the chest 1 is provided with a flange 2, and in said flange are apertures 13 for the passage of studs 14 through which the chest is bolted down on the old seat on the piston cylinder; the apertures 13 being by preference so arranged that the studs 14 will occupy the old holes in the said seat on the cylinder. The plan of the bottom of chest 1 conforms to the shape of the slide-valve steam chest it is designed to replace, and in said bottom are openings 6 that register with the port openings in the old seat on the piston cylinder. Around the openings 6 are grooves to hold copper-wire gaskets 8, designed to make a steam-tight joint when the chest 1 is tightened down by the studs 14.

Interiorly the chest 1 is provided with passages 15, one in vertical alignment with each opening 6, so that in effect the said openings 6 are prolonged or led up around the bushing 9 which is of standard type and provided with openings corresponding to the openings 6 and the passages 15. Formed in the chest 1 at 5 is a peep-hole, designed to be normally closed by a threaded plug (not shown). Said peep-hole is provided in order that the position of the valve can be seen from the outside of the chest. The interior construction of the peep-hole is shown in Fig. 3. When desired, the peep-hole may be duplicated at the same side of the chest and at the same distance from the transverse center of the chest as the peep-hole 5, without affecting our invention.

Exterior cavities 17 are cast in the chest 1 adjacent to the ends thereof to receive the heads of certain studs with a view to enabling the overhanging outside of the cylindrical portion of the chest to clear said heads. It will also be noted that the chest is provided adjacent to its ends with interior cavities 17^a (see dotted lines in Fig. 1) designed to receive the heads of certain studs in such manner that the bushing 9 clears said heads. The apertures complementary to the cavities 17 and 17^a are, like the apertures 13, so arranged, by preference, that studs placed therein will occupy old holes in

- the seat on the cylinder. In its top the chest 1 is preferably, though not necessarily, provided with holes 4 for holding relief or drifting valves (not shown) which form no part 5 of our invention and which may be omitted without affecting the same. Arranged over the chest 1 is a jacket or covering 3 of Russia iron or plain sheet-metal which is connected to the chest by bolts 20, threaded into 10 sockets 21 in the chest. Said covering 3 serves to hide the rough appearance of the casting and its appurtenances, and affords a smooth surface for painting or other finishing.
- 15 It will be gathered from the foregoing that the valve chamber of our novel chest is of very large diameter, as is desirable; also, that the chest does not entail the employment of a separate inner valve chamber 20 and the appurtenances thereof which manifestly renders it inexpensive and easy to repair. It will further be understood that after a slide-valve chest is removed from a locomotive cylinder, it is simply necessary 25 to plane down the valve seat and apply and connect our novel chest, after which the valve-operating mechanism that was employed to actuate the old slide-valve can be used to move the piston valve in bushing 9.
- 30 In this connection it is to be understood that the piston valve *per se* is of the ordinary-well-known construction, and that its stem operates the valve at the center thereof in the usual manner; said stem being car-

ried through a suitable stuffing box in one of 35 the heads.

Having described our invention, what we claim and desire to secure by Letters-Patent, is:

Means for the purpose described, comprising a cast-metal piston-valve chest having ends constructed and arranged for the connection of heads, and a bore extending between said ends, and also having a flat underside in which are openings arranged 45 to register with the ports in a locomotive piston-cylinder, and interior passages communicating with said ports and extending up and around said bore, and further having a base flange in which are apertures 50 for the passage of headed connecting studs, and interior cavities adjacent to its ends and stud apertures extending downwardly from the cavities; the said cavities being designed to enable the heads of studs to fall below and 55 clear a bushing; and the said bushing snugly arranged in the bore of the chest and constructed and arranged for the reception and operation of a piston-valve.

In testimony whereof we have hereunto 60 set our hands in presence of two subscribing witnesses,

LANCE L. DAWSON.
JOHN L. ROACH.
